(57) **CLAIM**

The ornamental design for a smartphone case with dual camera lens adapter, as shown and described.

DESCRIPTION

FIG. 1 is a front perspective view of a smartphone case with dual camera lens adapter showing my new design;

FIG. 2 is a front view of the smartphone case of FIG. 1;

FIG. 3 is a rear view of the smartphone case of FIG. 1;

FIG. 4 is a left side view of the smartphone case of FIG. 1;

FIG. 5 is a right side view of the smartphone case of FIG. 1;

FIG. 6 is a top view of the smartphone case of FIG. 1;

FIG. 7 is a bottom view of the smartphone case of FIG. 1;

and,

FIG. 8 is a rear perspective view of the smartphone case of FIG. 1.
